UNITED STATES PATENT OFFICE.

HARRY C. MALLORY, OF BELLPORT, NEW YORK.

HEAT-REGULATOR.

1,274,066.

Specification of Letters Patent. Patented July 30, 1918.

Application filed March 4, 1915. Serial No. 12,000.

To all whom it may concern:

Be it known that I, HARRY C. MALLORY, a citizen of the United States, residing at Bellport in the county of Suffolk and State 5 of New York, have invented certain new and useful Improvements in Heat-Regulators, of which the following is a full, clear, and exact specification.

This invention relates to improvements in 10 temperature regulators, and has particular reference to an improved apparatus whereby electric power is positively applied and controlled for operating valves which in turn control the flow of steam, hot water, or other 15 heating fluids through heating systems.

The present invention is particularly intended as an improvement over the pneumatic heat controlling systems now in common use, wherein a diaphragm operated 20 valve is actuated by pneumatic pressure, which pressure is controlled by a thermostat. Such pneumatic systems are complicated, expensive to install, and also require 25 constant attention after installation in order to keep in operative condition. One source of difficulty is the restricted air passage in the thermostat, which must be kept free from dirt and in proper adjustment, and frequent attention is required for this 30 purpose. Other automatic heat controlling systems have employed electromagnetically operated valves, but such systems have been found complicated and expensive and are not economical in consumption of current.

35 By the present invention, the original cost of the apparatus and installation is reduced and at the same time the apparatus is effective without the necessity of frequent inspection or adjustments. One form is 40 shown in the accompanying drawings, wherein

Figure 1 is a cross-section of the controlling thermostat, and

Fig. 2 is a cross-section of the thermostatically operated valve.

1 represents a boss on the end section of a steam radiator and containing a steam chamber 2, a steam inlet 3 and steam outlet 4 from the steam chamber 2. 5 is a valve seat, 6 a valve disk of composition material carried by a valve stem 7 and fastened by nut 8. The valve stem 7 is pressed around the bottom convolution of a flexible metal bellows 9, which is stiffened at the valve 50 end by means of the disk 10. The other end of the bellows 9 is pressed into a groove 12

carried by a shell 13, and an interior shell 11 is also pressed into the groove 12 of shell 13. The joint may be either hermetically sealed by solder or brazed so that the interior space between shell 11 and the interior bellows 9 can be filled with a volatile fluid, so as to form a fluid pressure thermostat. The shell 13 is screwed into the boss 1 as shown and its inner end also forms a 60 guide for the valve stem 7. Inside shell 11 is an electric heater 15 which is mounted on an insulating base 17. The insulating base 17 is bolted to an insulating base 18 by a bolt 19, and the base 18 carries the binding posts 20, 21, which are electrically connected with the resistance coils inside the heater 15. From the binding post 20, wire 22 leads to a moving switch terminal 27, and wire 23 70 may be connected with negative side of the supply line 28. The current is led from the positive side of the line 28 through wire 29 to contact post 30 in wall box 31, which will be at some desired place in the room where the temperature is to be regulated. It will 75 be seen that in the position shown the circuit is normally complete through movable switch 27 and stationary contact post 30, thus energizing the electric heater 15, causing the bellows 9 to expand and close the 80 steam valve 6. The wall box 31 carries a second bellows 33 which has an interior shell 34 similar to shell 11, and the bellows 33 and shell 34 are secured to a stationary head 35 carrying rods 36. The rods 36 85 carry a head 37 to which is attached through insulation 38 the movable contact 27. The bellows 33 and shell 34 are sealed similarly to bellows 9 and shell 11 and also contain a volatile fluid. The bellows 33 also has a 90 stiffening disk 39 similar to disk 10, and is similarly attached to movable head 37. 41 is a spring which normally forms a resistance against which the thermostat 33 operates, which resistance is adjustable by means 95 of a screw 45.

In the position shown, the circuit of the electric heater is complete, and the heat has been sufficient to close the steam valve 6. The temperature in the room then falls, 100 causing the volatile fluid in bellows 33 to condense, because this bellows was charged under a partial vacuum. The external air pressure then being greater than the partial vacuum, within the bellows 33, the latter is 105 collapsed, and moves the contact 27 so as to open the circuit of the electric heater. This 110

reduces the temperature and pressure in bellows 9, so that it will collapse on account of external air pressure and thus move the valve stem and open valve 6. The bellows

9 is located in the steam chamber 2 which is always open to the steam supply. This subjects the thermostat to a constant temperature which alone is not sufficient to close the valve, but which only requires a slight additional heat from the electric heater 15 to close the valve. Thus, there is much less work for the heater 15 to do in order to close the valve and consequently there will be a saving of current.

15 It will be understood that different fluids having different boiling points may be used in the two bellows 9 and 33.

These devices can be made very sensitive, and are especially adapted for controlling an electric circuit, owing to the relatively large movement produced by a comparatively small temperature change. It is possible to cause these devices to operate reliably within a variation of one degree of room temperature, which is much closer than prior devices of either the pneumatic or electromagnetic type, with which I am familiar, operate. It will be seen that the spring 41 can be adjusted so as to more or less balance the pressure of the fluid within bellows 33, it being seen that the expansion of spring 41 tends to collapse the thermostat bellows 33. Thus, any desired sensitiveness of bellows 33 can be obtained by balancing the vapor pressure of the fluid within the bellows 33 against the exterior atmospheric pressure assisted by the spring 41. Inasmuch as the bellows 33 is subject to ordinary heat fluctuations, it may be considered as a primary thermostatic controller, and the bellows 9 may be considered as a secondary thermostatic controller which controls the valve, but which is itself controlled by the fluctuations of the primary thermostatic controller.

45 The threaded shell 13 adapted to carry the bellows 9, the interior shell 11, and the electric heater 15, comprise a thermostatic valve unit which is capable of being attached to practically any of the standard radiator sections now in common use. This unit can be sold separately for attachment to the radiators of existing systems, and can be assembled and sold ready to be attached by simply screwing it into the boss and properly adjusting the valve with the valve seat. For this purpose, the interior of the radiator can readily be provided with a valve seat 5, or one can be supplied with the unit. Thereby, the entire device can be installed without requiring expensive fittings or attachments, or require special radiator construction. As herein shown, the supporting shell 13 is extended so that it forms a guide for the movable valve stem

7, which slides loosely therein, but at the same time allowing sufficient flexibility so that the valve disk 6 will tightly fit the seat 5 when the bellows is expanded.

70 The invention is shown herein in a preferred application, but in addition to being useful for controlling the flow of fluids according to temperature variations, it has various other uses within the scope of the appended claims, and of course various 75 modifications and changes in the specific details herein shown may be made without departing therefrom.

Having thus described my invention, I declare that what I claim as new and desire to secure by Letters Patent, is:—

80 1. The combination with a primary circuit controller, of an electric circuit, a secondary heat actuated controller, means for maintaining said secondary heat actuated controller at a normal elevated temperature, a heater in said electric circuit for raising the normal temperature of said secondary heat controller to a higher degree and a device adapted to be moved to one position when said secondary controller is normally heated and to another position when abnormally heated.

85 2. The combination with a primary thermostatically actuated circuit controller, of an electric circuit, a secondary heat actuated controller, means for maintaining said secondary heat actuated controller at a normal elevated temperature, a heater in said electric circuit for raising the normal temperature of said secondary heat controller to a higher degree, and a device adapted to be moved to one position when said secondary controller is normally heated and to another position when abnormally heated.

90 3. The combination in a temperature controlling system, of an electric circuit, a primary circuit controller therein, a fluid circulating passage, a controller therefor normally controlled by the fluid temperature in said passage, and a heater in said circuit for raising the normal temperature of said controller above the normal fluid temperature for moving said controller to another position.

100 4. The combination in a temperature controlling system, of a fluid passage containing a valve, a thermostat in the supply side of said passage for actuating said valve, said thermostat when subjected to the normal fluid temperature holding the valve in one position, and means for raising the temperature of said thermostat above the normal fluid temperature to move said valve to its opposite position.

105 5. The combination with a source of fluid supply, of a radiator or the like to be supplied thereby, a controlling valve for the fluid supply thereto, a thermostat on the supply side and subject to the fluid tem-

perature, for operating said valve in one direction, and means for additionally heating said thermostat to move said valve in the opposite direction.

5 6. The combination with a source of fluid supply, of a radiator or the like to be supplied thereby, a controlling valve for the fluid supply thereto, a thermostat on the supply side and subject to the fluid temperature, for operating said valve in one direction, and thermostatically controlled means for additionally heating said thermostat to move said valve in the opposite direction.

10 7. The combination with a source of fluid supply, of a radiator or the like to be supplied thereby, a controlling valve for the fluid supply thereto, a thermostat for opening said valve when subjected to the supply fluid temperature, an auxiliary electric heater for said thermostat, a second thermostat located at a distance from said valve, a switch controlled by said second thermostat, and an electric circuit between said heater and said switch for controlling said

25 8. The combination in a temperature controlling system, of a fluid passage containing a valve, a thermostat in the supply side of said passage for actuating said valve, said thermostat when subjected to the normal fluid temperature holding the valve in one position, and means controlled by a distant temperature for raising the temperature of said thermostat above the normal fluid temperature to move said valve to its opposite position.

30 9. A valve element adapted for insertion in the flow to a radiator comprising a support, a fluid pressure bellows type thermostat closed at one end and attached to said support at its opposite end, a movable valve externally carried by said closed bellows end, and a shell carried by said support extending within the bellows and closing its

45 open end.

10. The combination with a valve, of a fluid pressure operated thermostat normally holding the valve open, means supplying heat to the thermostat in degree almost but not quite enough to close the valve, a supplemental heater for said thermostat to close the valve, a circuit for said supplemental heater, and a second fluid pressure thermostat for controlling the circuit of said

55 heater.

11. The combination with a fluid pressure operated bellows type thermostat closed at

one end, of a shell within said thermostat closing the other end thereof, and an electric heater within said shell.

60

12. The combination with a valve, of a fluid pressure operated bellows type thermostat closed at one end, a shell within said thermostat closing the other end thereof, an electric heater within said shell for heating said thermostat to move the valve in one direction when heated, and means for controlling the supply of current to said heater.

65

13. The combination with a valve, of a fluid pressure operated bellows type thermostat closed at one end, a shell within said thermostat closing the other end thereof, an electric heater within said shell for closing the valve, and means for controlling the supply of current to said heater to open and close the valve.

70

14. The combination with a fluid pressure operated bellows type thermostat closed at one end, of a shell within said thermostat closing the other end thereof, and adjusting means within said shell for controlling the movement of said thermostat.

75

15. A valve element for a radiator or the like, comprising a support adapted to be attached to the radiator, a fluid pressure operated bellows type thermostat closed at one end and attached to said support at the opposite end, a movable valve element carried by said closed end, means closing the other end of said thermostat, and an electric heater within said means.

80

16. The combination with a radiator section having a projecting boss, of a valve element comprising a support adapted to be attached to said boss, a fluid pressure operated bellows type thermostat closed at one end and attached to said support at the opposite end, a movable valve element carried by said closed end and coöperating with a valve seat carried by said boss, a shell closing the other end of said thermostat, and an electric heater carried by said support within said shell for controlling said valve.

85

17. A fluid pressure actuated thermostat comprising concentric flexible and rigid walls, and an electric heater near said rigid wall, for operating said thermostat in one direction.

90

In testimony whereof I affix my signature in presence of two witnesses.
